UNITED STATES PATENT OFFICE

JOHN W. WOLFE, OF CANTON, OHIO, ASSIGNOR TO THE UNITED ELECTRIC CORPORATION,
OF CANTON, OHIO, A CORPORATION OF OHIO

SUCTION CLEANER

Application filed September 9, 1932. Serial No. 632,341.

The invention relates in general to suction cleaners, and in particular to agitating and sweeping means located in the suction nozzle of the cleaner for beating the floor covering as the nozzle passes thereover.

It is obviously desirable for general purposes to provide sweeping means as well as agitating means within the nozzle, for removing lint, threads and the like from the surface of the floor covering. In the past, certain suction cleaners have been provided with a rotary member having both beating and sweeping means thereon, but with that arrangement the beating and sweeping efficiency of the rotary member is necessarily much lower than if these functions are performed by separate elements.

It is therefore an object of the present invention to provide a suction cleaner having separate means for beating and sweeping a floor covering.

Another object is to position the agitating and sweeping means within the suction nozzle of the cleaner in such a way as to perform their respective functions in the most efficient manner.

A further object is to drive both the agitating and sweeping means from the motor of the suction cleaner.

Another object is to provide agitating and sweeping means which are positioned and designed so as not to detract materially from the amount of suction acting upon the floor covering by greatly increasing the size of the suction nozzle.

A still further object is to provide agitating means adapted to be located in closely adjacent non-interfering relation to the sweeping means, the agitating means being so designed as to strike a series of abrupt blows upon the floor covering.

And finally, it is an object of the present invention to embody all of the foregoing objectives in a simple and light weight construction, which is extremely economical to manufacture.

These and other objects are attained by the improvements comprising the present invention, which may be stated in general terms as including in a suction cleaner having a suc-

tion nozzle and a motor, a brush member rotatably mounted in the suction nozzle, an agitator bar preferably located in front of the brush and having in cross section a relatively small oblong shape with rounded ends, 55 and means operatively connecting the brush member and the agitator bar to the motor.

Referring to the drawing forming part hereof,

Figure 1 is a fragmentary plan view of a 60 suction cleaner embodying my invention, as on line 1—1, Fig. 2, parts of the nozzle being broken away;

Fig. 2 is a fragmentary side view, partially in section and partially in elevation, taken 65 substantially on line 2—2, Fig. 1; and

Fig. 3 is a fragmentary sectional view, as on line 3—3, Fig. 1.

Similar numerals refer to similar parts throughout the several views. 70

In the drawing 10 represents the motor of a suction cleaner embodying my invention, the shaft 11 of the motor extending through the fan chamber 12, in which the usual suction fan 13 is located, being secured 75 upon the motor shaft 11.

The suction nozzle, indicated at 14 is located adjacent to the fan chamber 12 and communicates therewith through the passageway 15 and aperture 15'. The usual 80 dust collecting bag 16, is detachably secured to the exhaust end 17 of the fan housing, in a well known manner.

The suction cleaner is rollably supported upon the floor covering 18 by front rollers 85 19 and the rear roller 20, in such a manner that the bottom of the nozzle is positioned a substantial distance above the floor covering.

The nozzle 14 is formed by the end walls 90 21, and the top and front wall member 23. The improved sweeping means and beating or agitating means are located within the nozzle.

The sweeping means comprises the rotatable brush 24, having the circumferentially arranged bristles 25 upon the shaft 26, and the shaft is journaled at the end walls 21 in bearings 27, which may be bronze bushings. The brush should have a substantial 100

outer diameter, providing a relatively large area for efficiently sweeping the floor covering. Accordingly, the brush 24 preferably has an outer diameter substantially equal to the depth of the nozzle 14. The brush shaft 26 is preferably provided at its central portion with a pulley 28, and a flexible belt 29 preferably operatively connects the pulley 28 with the motor shaft 11.

- 10 The improved agitating means preferably includes the agitator bar 30, which is rotatably mounted in the nozzle 14 in front of and closely adjacent to the brush 24. The agitator bar 30 preferably has a pulley portion 31 at or near its central portion, and a flexible belt 32 operatively connects the bar 30 to the brush shaft 26, so that the agitator bar is driven from the motor 10.

15 The portion of the agitator bar 30 at each side of the pulley 31 preferably has in cross section an oblong shape with rounded ends, as best shown in Fig. 2. By making the bar 30 small relative to the brush 24, that is, by making the greatest cross sectional dimension of the bar materially less than the greatest cross sectional dimension or the outer diameter of the brush 24, two very important advantages are realized.

20 First, the agitator bar may be located closely adjacent to the brush in non-interfering relation thereto, so that the nozzle area is not increased to an extent which detracts from the amount of suction acting upon the floor covering, when the same is sucked up 25 against the nozzle by the air current supplied by the motor.

Second, when the agitator bar is rotated it will strike a series of abrupt blows upon the floor covering, because the rounded ends of 40 the bar travel a small arcuate path and strike the floor covering more directly, and therefore more suddenly and sharply than if the bar were larger. If the bar were larger, the striking portions thereof would travel a 45 greater arcuate path and strike the floor covering more nearly tangentially.

In other words, when the bar 30 is made relatively small, the ends thereof will strike the carpet sharply and abruptly to give a 50 positive beating action, whereas, a larger bar would give more of a wiping action, resulting in a marked decrease of beating efficiency.

55 The outer ends of the agitator are journaled in bearings 34, which may be bronze bushings similar to the bearings 27. At each end of the nozzle 14, the bearing 34 is mounted in one end of a plate 35, which has its other end pivotally secured to the adjacent 60 end wall 21, as at 36. At its bottom edge each plate 35 is preferably provided with an outturned flange 35' fitting under the adjacent end wall 21, for limiting the upward movement of the plate into the nozzle.

65 The bearings 34 and 27 at each end of the

nozzle are mounted in a plate 37 located inside of the plate 35 at that end of the nozzle.

Each plate 37 is detachably connected at its upper end to the adjacent plate 35, as by a pin 38 which is entered in one of a series 70 of holes 38' provided in plate 35, and each plate 37 may be secured, as by welding, to a transverse connector bar 39 which is located adjacent to the front wall of the nozzle.

The brush 24 and agitator bar 30, together 75 with the plates 35 and 37 and connector bar 39, provides a brush and agitator assembly, which, when the belts are disconnected, may be swung downwardly about pivots 36 out of the nozzle, a notch 40 being provided in each 80 plate 35 for fitting around the rear lip 41 of the nozzle.

In operative position, the brush and agitator assembly is held in the nozzle by the pull of belts 29 and 32, the flanges 35' abutting the bottom edges of nozzle end walls 21. As the brush becomes worn off, it may be lowered relative to the nozzle and to the agitator bar by entering the pin 38 of each plate 37 in another of the holes 38' provided in 90 plates 35, the plates 37 pivoting at bearings 34.

It is well known that the bulk of the work done by a suction cleaner is accomplished during its forward movement, the rearward movement thereof coinciding with or considerably overlapping the next preceding forward movement. Consequently, by locating the agitator bar in front of the brush, the highest possible cleaning efficiency is obtained, because the portion of the carpet immediately in front of the brush is agitated to loosen lint, threads and the like which are picked up by the brush, as well as all other dirt which is immediately sucked up by the 100 nozzle.

The present improved construction is simple and light in weight, and economical of manufacture.

I claim:—

1. In a suction cleaner having a suction nozzle and a motor, a rotatable brush journaled in the nozzle and having an outer diameter substantially equal to the depth thereof, an agitator bar having a portion shaped oblong with rounded ends in cross section, said agitator bar being rotatably mounted in the nozzle in front of and closely adjacent to the brush the greatest cross sectional dimension of the agitator bar being materially less than the outer diameter of the brush and means operatively connecting the brush and agitator bar to the motor.

2. In a suction cleaner having a suction nozzle and a motor, a rotatable brush journaled in the nozzle, an agitator member rotatably mounted in the nozzle in closely adjacent non-interfering relation to the brush, the greatest cross sectional dimension of the agitator member being materially less than 130

the greatest cross sectional dimension of the rotatable brush, and means operatively connecting the brush and agitator member to the motor.

5 3. In a suction cleaner having a suction nozzle and a motor, a rotatable brush journaled in the nozzle, an agitator bar of small cross sectional size relative to the brush and having a portion shaped oblong with rounded ends in cross section and rotatably mounted in closely adjacent non-interfering relation to the brush, and means operatively connecting the brush and the agitator bar to the motor.

10 4. In a suction cleaner having a suction nozzle and a motor, a brush rotatably mounted in the nozzle, an agitator of small cross sectional size relative to the brush rotatably mounted in the nozzle closely adjacent to the brush, and means operatively connecting the brush and agitator to the motor.

In testimony that I claim the above, I have hereunto subscribed my name.

JOHN W. WOLFE.
